UNITED STATES PATENT OFFICE.

CHARLES GREENSLIT, OF CLEVELAND, OHIO, AND ROSCOE ROYAL, OF CHICAGO, ILLINOIS, ASSIGNEES TO THE BATTERY BALL MANUFACTURING COMPANY, OF CLEVELAND, OHIO, A CORPORATION OF MICHIGAN.

AMUSEMENT DEVICE.

1,188,646.

Specification of Letters Patent. Patented June 27, 1916.

Application filed September 11, 1913. Serial No. 789,370.

To all whom it may concern:

Be it known that we, CHARLES GREENSLIT, residing at Cleveland, in the county of Cuyahoga and State of Ohio, and ROSCOE ROYAL, residing at Chicago, in the county of Cook and State of Illinois, both citizens of the United States, have invented certain new and useful Improvements in Amusement Devices, of which the following is a full, clear, and exact description, reference being had to the accompanying drawings.

This invention relates to amusement devices and particularly to an apparatus whereby the American game of baseball can be easily and accurately played. However, while we shall describe our improvement entirely with reference to the American game of baseball, it will be understood that with suitable changes in construction, design, and nomenclature, the devices of our invention could be employed in connection with other contests, such as rifle matches, archery matches, shooting galleries, cricket, golf, etc., and it will also be apparent that some of the features of the apparatus are susceptible of a broader use, such as signaling and registering generally. Accordingly it will be understood that the following description, although confined to the use and arrangement of the invention according to the game of baseball, is intended to be illustrative merely, and not definitive of the limits of the invention.

In the patent to Culp, No. 1,018,409, dated Feb. 27, 1912, there is illustrated, described and claimed an apparatus for playing the game of baseball, comprising a yielding curtain, a bat movable across said curtain, and electric contrivances associated with various parts of the curtains and the bat, so that while one player shall pitch or throw baseballs at the curtain, another player, by the manipulation of suitable devices, may shift the bat in attempts to intercept the ball, and electric devices will be actuated depending upon the relative success of the two players to expose indications corresponding roughly to the decisions of the umpire and the actual progress of a real base ball game. The mechanism of this prior device was crude and unsatisfactory in certain respects, partly because of the difficulty of keeping the fixed target mechanism in operative condition, owing to the fact that the curtain was frequently torn away by the

ball, partly by reason of the weight of the bat, and because of the difficulty of shifting the same, partly because of the great rebounding of the ball which caused it to miss the retrieving mechanism, and partly because of the unsatisfactory nature of the electrical contacts.

It is the main object of this invention to provide new and useful expedients whereby the above named difficulties may be avoided, such as the provision of new and improved means for supporting the various targets; the provision of new and improved contact devices for those targets; the provision of a new and simplified form of movable target or bat; the provision of new and improved means for operating said bat; the provision of new and improved devices for returning the ball to the players; the provision of mechanism which can be readily packed into small compass and shipped or transported, and easily set up upon occasion; while further objects and advantages will become apparent as the description proceeds.

It is a well known fact that the interest in a baseball game centers particularly about the pitcher and batter, and among amateur baseball enthusiasts the positions of batter and pitcher are most eagerly sought, the other positions being taken only upon sufferance or due regard for fair play. However, it has always been necessary in order that two persons should test their respective powers in pitching and batting to obtain the services of a large number of others for the purpose of fielding the ball. We have therefore striven to perfect an apparatus which can be set up at parks, pleasure resorts, bowling alleys, fairs, expositions, and the like, so as to enable baseball enthusiasts to test their respective powers without such outside assistance, the apparatus being easily transportable so as to enable its owner to follow the crowd.

In the present and most desirable embodiment, this apparatus may be conveniently divided into, A, target and its accessories by which the impact of the balls is received; B, the registering device or "umpire" by means of which the impact of the balls upon the target is recorded together with the place of such impact; and C, the retrieving mechanism by means of which the balls are recovered and returned to the players.

In the drawings accompanying and forming part of this specification, wherein one embodiment of our improved device is illustrated, Figure 1 is a perspective view of the complete apparatus; Fig. 2 is a central, longitudinal, vertical, cross-sectional view through the target mechanism, retrieving mechanism, and the associated parts; Fig. 3 is a plan view of the parts shown in Fig. 2; Fig. 4 is a vertical, transverse, cross-sectional view taken through the retrieving mechanism, the target being shown in elevation; Fig. 5 is a detail view of a portion of one of the targets, showing the contact-making devices; Fig. 6 is a longitudinal cross sectional view through the movable target or "bat"; Fig. 7 is a detail view of one of the contacts carried by the movable target or bat; Fig. 8 is a perspective view of the bat-supporting member; Fig. 9 is a cross sectional view of the bat taken on the line 9—9 of Fig. 6; Fig. 10 is a plan view of one of the relays employed in the registering mechanism or umpire; Fig. 11 is a detail view of a portion of the retrieving mechanism; and Fig. 12 is a diagram of the electrical connections employed. For purposes of clearness the various general divisions of the apparatus will be described separately, beginning with the first.

A. Target mechanism.—Supported in upright position, at the proper distance from the pitcher's box 1 at right angles to the line drawn from that box, is a rectangular frame-work 2, preferably of knock-down construction, having at its lower end suitable cross pieces 3 and adjacent to its upper end suitable brackets 4 and 5 respectively. Journaled between the brackets 4 is a horizontal roller to which is secured a curtain 7 of cloth or other suitable flexible material, the lower end of which is fixed to the cross piece 3. This curtain is formed with an oblong aperture 8 of the shape and area within which pitched balls can be denominated strikes. Similarly journaled in the brackets 5—5 is a horizontal roller 9 upon which is wound a suitable curtain 10 which falls immediately behind the aperture 8 and like the curtain 7 is attached to the cross pieces 3—3. The curtain 10 is preferably provided with a hood 11, also of flexible material, and held in place by suitable springs so as to prevent balls thrown thereagainst from falling upon the floor behind the curtain, and causing them to be delivered back through the aperture 8. These curtains are maintained in taut position by means of suitable springs (not shown) concealed in the rollers, ordinary shade rollers being conveniently employed for the purpose; and arrangements are provided whereby electric contacts will be made upon the rotation of these rollers when the curtains are displaced as by balls striking the same. For making this contact,

the most satisfactory expedient which we have yet hit upon is that illustrated in Fig. 5, wherein the end of each roller is formed with a helical groove 13 and the bracket is provided with an insulated flexible spring 70 finger 14 having its free end projecting into said groove. Upon the rotation of the roller 9 the spring finger 14 moves laterally into contact with a fixed contact member 15 and thus sets in operation the registering mechanism hereinafter described. This arrangement causes a small displacement to make a sufficiently long contact for the purposes of registration and prevents a heavy blow from distorting the contact mechanism. Preferably the finger 14 is arranged so as to tend to engage the fixed member 15, since this arrangement causes a firmer and steadier contact to be made than if the cam action is relied upon to force the members together. 80 Also the fixed member 15 is preferably made yielding so as to prevent any possibility of permanent distortion by reason of an unusually great displacement of the parts.

Supported in front of the fixed target 90 arrangement heretofore described is a movable target device, here taking the form of a narrow elongated member which we term the "bat". In the present embodiment, this "bat" is pivoted upon a horizontal axis at 95 one side of the curtain 7 and is arranged to be swung up or down across the aperture 8 to meet the expected direction of the balls delivered by the pitcher. In the present embodiment, a trough shaped supporting 100 member 18 is provided having parallel sides 19—19 and connected by a rigid end piece 20. This trough member is securely attached to a spindle 21 which is journaled in a box 22 carried by the upright 2 and has upon 105 its opposite end a sprocket wheel 23 engaged by a chain 24 whose ends are connected by wires 25—25 with a lever 26 supported adjacent to the batsman's position so as to enable the latter to shift the bat to intercept 110 the balls delivered. The spindle 21 is also provided with an arm 28 to which is secured a spring or like counterbalancing device 29 by means of which the "bat" may be held in any position to which it is moved.

Secured to the member 18, as by means of links 30—30 pivoted to the sides 19 thereof, is a beam 31, here shown as of metal rolled into U-shape and having its open edge presented toward the curtain. The links 120 30—30, being pivoted to the sides 19 of the trough member and to the sides of this U-beam, form a kind of parallel motion, the beam being normally held in forward position by means of a tension spring 32 secured 125 thereto and to the end piece 20. This arrangement is adapted so that when the "bat" is struck by a ball at any point it may yield sufficiently to prevent any undue strain from being brought upon the apparatus.

Yieldingly secured to the beam 31 are a plurality of cushions 33—33, each of which is mounted upon a channel member 34 which straddles the beam 31 as shown in Fig. 2. These channel members are yieldingly mounted for parallel motion in any suitable manner as by the links 35—35 herein shown, and are yieldingly held away from the beam 31 by means of suitable springs 36. Contact members are arranged so as to be actuated by the shifting of the members 34 toward the beam 31, the arrangement shown herein comprising a pair of springs 37, normally held in separated position, as by the pressure against one of them of the button 38 (Fig. 7) but arranged to be brought into contact with each other upon the movement of said button away therefrom, the button being connected to one of the members 34. In the present embodiment, the portions of the "bat" are connected so as, when hit by the ball, to register "fouls," "hits," or "home-runs," as indicated in Fig. 6, though it will be obvious that the portions of the bat could be differently arranged or that different names or denominations could be given to them, and that the shape and arrangement of the movable target could be changed entirely without departure from my invention. The mode of operation of the various targets will probably be clear without further description.

B. Registering device or "umpire".— The wires over which the impulses are to be received are brought together to a central point and connected in a system whose arrangement and layout will depend upon the quantities to be registered, although in the present description we shall confine ourselves to an elucidation of its arrangement when used for registering the events of a base ball game. However, the variations necessary to adapt the registering mechanism for use with other games or the annunciation of other quantities will readily occur to those skilled in the art.

For use with a base ball apparatus the registering mechanism is preferably contained within a cabinet 38, having upon its face the representation of a base ball diamond, said cabinet being connected to the target mechanism by means of a suitable cable 39. The corners of the diamond are provided with suitable annunciators, preferably small incandescent lamps indicated at 40 and the pitcher's box may have a lamp 41. The face of the cabinet may also bear at convenient locations other series of lamps as 42 for indicating the number of "strikes"; 43 for indicating "balls"; 44 for indicating "outs"; and 45 for indicating "runs". Other annunciators than lamps may obviously be employed, but lamps are particularly convenient from the fact that they

automatically return to their previous condition immediately upon the cessation of the current through them. A great many expedients could be employed for actuating these annunciators upon the occurrence of contacts at the different parts of the target mechanism, but for purposes of completeness I have illustrated herein an extremely simple form of circuit, although it will be understood that any suitable or desired circuit arrangement could be employed within the scope of the invention herein claimed.

One form of relay which can be employed in connection with the simple circuit here described is illustrated in Fig. 10, and the various connections in diagrammatic form in Fig. 12. The relay here disclosed consists of an electromagnet 48 having an armature 49 and provided with the usual contacts. Journaled in the frame of the relay is a rock shaft 52 having secured to its outer end an arm 53 and to its inner end a finger 54 terminating at its end in a laterally turned tip 55 adapted to overhang the edge of the armature.

A suitable spring 56 coiled about the shaft 52 tends to rotate this shaft so as to bring the finger 54 into contact with a terminal 57 mounted within the relay frame but insulated therefrom. Normally the tip 55 will overhang the side of the armature and thus be maintained out of contact with the terminal 57, but upon the energization of the magnets 48 the armature 49 will be displaced so as to permit the rotation of the shaft 52 by the spring 56 and thus make contact with the terminal 57. The arm 53 carries a button or indicator 58 which, by its displacement, indicates visually the fact that the magnet has been actuated, each of those buttons or indicators carrying the appropriate term of the event which is recorded. In the present embodiment these relays are shown as mounted upon the exterior of the cabinet 38, and beside them are mounted switches as follows: 60 for "strikes", 61 for "balls", 62 for "runs", 63 for "outs", and 64 for "home runs", said switches being adapted to coöperate with contacts *a*, *b*, *c*, respectively, connected with the individual lamps of the previously described series. Other switches 65, 66 and 67 are provided for the different "bases". The relays are restored to original position after each actuation by lifting the arm 53 by hand. The pitcher's lamp is not here employed for any indicating purpose except to indicate that the machine is in play. This is particularly desirable in the case of a coin controlled device, although no coin mechanism is herein illustrated.

Referring to Fig. 12 wherein is illustrated diagrammatically the circuits employed, the "strike" relay is indicated at *S*, the "ball" relay at *B*, the "hit" relay at *H*, and the "home run" relay at *X*, each of the same

being constructed substantially as previously described. From the battery extends a main lead 70 connected to the various contacts 72, 73, 74 and 75 at the targets. From these contacts wires 76, 77, 78 and 79 respectively extend to the various relays. The finger 54 of each relay and the armature 49 thereof are connected in parallel and joined to one terminal of the corresponding magnet, the other terminal of the magnet being connected to the return main 80. The various switches may also be connected to the return main 80, the various lamps being connected to the opposite side of the battery as by the main 81. Also the main 70 is provided with a branch 82 connected with the terminals 57 of the various signals.

Supposing a contact to be made at 72 as by the impact of a ball against the curtain 20 10: an impulse will pass from the battery by way of 70, 72, 76 and S49 to the magnet of the relay S, thus causing the attraction of the armature 49 and permitting the swinging of the finger 54. This causes a change in 25 the position of the corresponding indicator 58, and may also effect the ringing of a bell 83 or a production of some other sensible signal, the actuation of this mechanism being continued by the circuit from the battery 30 through the branch 82 and contact 57, since the contact at 72 is usually only momentary. Thereupon a player or attendant, noting that the indication is for a "strike" 35 will shift the switch 60 onto the point 60^a, thereby illuminating the corresponding lamp 42^a. The relay is then restored to its original condition by shifting the arm 53, whereupon the apparatus is ready for another operation. The method of keeping 40 track of the various scores will probably be clear without further description.

C. Ball retriever.—In order to minimize the necessity for an attendant, we prefer to employ automatic means for returning the balls to the players, and have therefore devised the following improvements upon the apparatus illustrated and disclosed in the Culp patent, heretofore mentioned: To this end, we provide in front of the curtains 7
45 and 10, a basket or receptor comprising a canvas or other sheet 125 stretched within a horizontal, rectangular frame work 126, and having at a suitable point an aperture 127
50 for the discharge of the balls which fall thereon. In order to provide a device which can be set up on top of a floor, such as a billiard alley, and without the necessity of sinking any part of it, we suspend this receptor a convenient distance above the floor
55 as shown in Fig. 2, and place in front of the same an inclined shield 128. Beneath the aperture 127 we provide a conduit 130 whereby the balls are conveyed to the elevator which is best shown in Fig. 4. This
60 elevator comprises a frame or standard 131
65

having at its upper and lower ends sprocket wheels 132 and 133, respectively, the latter being adjacent to the mouth of the conduit 130, as shown in Fig. 4. Surrounding these sprockets is a chain 134 provided at intervals with projecting fingers 135 adapted to engage the balls as they emerge from the conduit 130. The upwardly moving leg of the chain is inclosed in a casing 136 which at the top merges with spout 137, and this spout discharges into a suitable trough 138 whereby the balls are returned to the players. For driving this mechanism, we preferably employ an electric motor 140 supported upon a suitable part of the frame 80 work and communicating by means of a belt 141 and countershaft arrangement 142 with a pulley 143, affixed to the sprocket 132. In connection with this sprocket we also preferably employ a third pulley or sprocket 85 144 secured thereto in one-way-driving-relation, as by means of the ball clutch 145, and connected by means of the chain 146 and wire 147 with the lever 148 adjacent to the pitcher's box, so that, if for any reason, the 90 electric drive should be impossible or inoperative, a manipulation of this lever will serve to set the apparatus in operation and retrieve any balls which may be present at the far end of the apparatus. We find that 95 with the arrangement illustrated and described a single manipulation of the lever 148 will impress a sufficient degree of speed upon the retriever mechanism to raise a considerable number of balls and return them 100 to the players.

While we have described in detail a specific use of our invention, it will be apparent that departures, both from the details and from the use, may be made without exceeding the scope of our inventive idea. Many such departures from the use have been suggested in the foregoing description, and many others will occur to any mechanician, while the possible variations in detail are so great that it is impracticable to describe them all. However it is thought that the construction and operation of our improvements will be clear to those skilled in the art without more extended description. 110 115

Having thus described our invention, what we claim is:—

1. In amusement apparatus, in combination, a pair of substantially vertical targets mounted one in front of the other, the foremost target being of flexible material yieldingly mounted and having an aperture arranged so as to disclose a portion of the rearmost target, said rearmost target also being yieldingly supported, a movable target mounted in front of said first target, electrical contacts carried by the respective first and said movable targets and adapted to be closed upon the impact of a missile thereagainst, and operative connections to said 120 125 130

movable target whereby the same may be operated from a distance to intercept missiles hurled at said first named targets.

2. In mechanism for receiving and recording the impact of a missile, the combination of a target frame, a roller carried thereby, a flexible curtain carried by said roller, movable fingers mounted adjacent to said roller, electrical contact devices carried by said fingers, and means carried by the roller and engaging with one of said fingers upon the rotation of said roller for displacing said finger and closing the circuit through said contact devices.

15. 3. In mechanism for receiving and recording the impact of missiles, in combination, a frame, a roller carried thereby and having a helically grooved portion, a curtain wound upon said roller, movable fingers carried by said frame and projecting into said groove so as to be displaced upon the rotation of said roller, and electrical contact devices carried by said fingers.

4. In mechanism for receiving and recording the impact of a missile, the combination of a target frame, a displaceable supporting device carried thereby, a flexible curtain secured to said supporting device, movable fingers mounted adjacent to said supporting device, electrical contact devices carried by said fingers, and cam means carried by said supporting device and operative upon the displacement of the same for bringing said fingers together closing the circuit through said contact devices.

5. In mechanism for receiving and recording the impact of missiles, in combination, a frame, a roller carried thereby and having a cam thereon, a curtain wound upon said roller, movable fingers carried by said frame and projecting adjacent to said cam so as to be displaced upon the rotation of said roller, and electrical contact devices carried by said fingers.

45. 6. In game apparatus, a movable target comprising a hollow beam, one or more movable sections carried by said beam and supported for movement toward and from the same, means yieldingly maintaining said sections in a position away from said beam, contact fingers carried by said beam, and means operative by the movement of said sections relatively to said beam for making and breaking the contact at said fingers.

55. 7. In mechanism of the character described, the combination, with a support and a pair of spring fingers carried thereby, said fingers having portions adapted to contact with each other and being arranged so as normally to make such contact, of a movable member carried by said support and adapted to be displaced upon the impact of a missile thereagainst, cam means normally maintaining said fingers out of contact with each other, and connections between said

movable member and said cam means whereby said cam means will be displaced upon the displacement of said movable member and the contact of said fingers permitted.

8. In impact registering mechanism, the combination, with a support and a spring finger carried thereby, of a fixed contact which said finger tends to engage, a movable member carried by said support, a camming device operatively connected to said movable member and adapted when moved in one direction to separate said finger and fixed contact, and yielding means connected to said movable member and normally maintaining said camming device in a position to hold said finger out of engagement with said fixed contact.

9. In impact registering mechanism, the combination with a rigid support, of a member movably supported thereby upon a pair of parallel axes so as to be movable toward and from said support in a direction normal to the plane containing said axes, a pair of contacts carried by said support, a cam device carried by said movable member and adapted to engage said contacts, spring means connected to said movable member and support and normally holding the same separated and simultaneously maintaining said cam device in the position it assumes when said contacts are separated, said cam being arranged so that upon movement of said member toward said support said contacts shall touch each other.

10. In mechanism for receiving and recording the impact of missiles, the combination, with a fixed, yielding target supported in substantially vertical position, of a supporting member journaled at one side of said fixed target upon a substantially horizontal axis, an elongated beam connected to said supporting member and projecting across the face of said target, such connection being of a nature to permit lateral movement of said beam while maintaining it always parallel to the plane of said target, means yieldingly connecting said beam and supporting member whereby the former is yieldingly held away from said fixed target, electric contacts carried by different parts of said beam and by said fixed targets and adapted to be operated by the impact of missiles thereagainst, and means for swinging said beam across the face of said fixed target.

11. In mechanism for receiving and recording the impact of missiles, in combination, a movable target comprising a support, a plurality of rigid members, links pivoted to said support and to said rigid members so as to permit the latter to move in a parallel manner, electric contacts adapted to be made and broken upon the displacement of said rigid members, and yielding means normally maintaining said rigid members at

their point of greatest displacement from said support.

12. In baseball game apparatus, in combination, a bat consisting of an elongated beam, a support therefor, means pivotally securing said beam to said support, U-shaped members straddling said beam and yieldingly secured thereto, springs connected to said members and to said beams and tending to maintain said members at a point away from said beam, and electric contacts carried by said beam and adapted to be made and broken upon the displacement of said members.
13. In game apparatus, the combination, with an upright target and contacts carried thereby, of an elongated supporting member pivoted upon a substantially horizontal axis at one side of said target, means connected to said member and extending to a distance therefrom whereby said member can be swung past said target, means connected to said member and tending to counterbalance the weight thereof, and contact members carried by said supporting member and adapted to be actuated by the impact of a missile thereagainst.
14. In baseball game apparatus, in combination, a bat consisting of a U-shaped metal beam, a support therefor, means pivotally securing said beam to said support, U-shaped members straddling said beam, the sides of said members and of said beam being substantially parallel, links pivoted to the sides of said beam and members respectively, so as to permit said members to move toward and from the same, cushions carried by said members, springs connected to said members and to said beams and tending to

maintain said members at a point away from said beam, and electric contacts carried by said beam and adapted to be made and broken upon the displacement of said members.

15. Retrieving apparatus for games involving the casting of missiles, comprising a receiver for said missiles, elevating apparatus for raising the same from the receiver, a motor operatively connected to said apparatus, an inclined trough adapted to receive said missiles from said apparatus and return them, and manually operated means also connected to said elevating apparatus for operating the same when desired, independently of the motor.

16. The combination, with game apparatus, of a retriever for missiles comprising a receptor for said missiles, a spout adapted to receive missiles from said receptor, an endless chain mounted in inclined position and adapted to receive said missiles from said spout and elevate the same to a position higher than the players, an inclined trough adapted to receive said missiles and convey them to the players, means for automatically driving said chain, and devices connected to said chain driving means and adapted to be moved manually to operate said retrieving apparatus upon the failure of said automatically driving means.

In testimony whereof, we hereunto affix our signatures in the presence of two witnesses.
